(57) **CLAIM**

The ornamental design for a muffler exit pipe for motorcycles, as shown and described.

DESCRIPTION

FIG. 1 is a front elevational view of a muffler exit pipe for motorcycles showing my new design;
FIG. 2 is a rear elevational view thereof;

FIG. 3 is a left side elevational view thereof;

FIG. 4 is a top plan view thereof;

FIG. 5 is a bottom plan view thereof; and,

FIG. 6 is a rear left perspective view thereof.

The claimed design is a muffler exit pipe for motorcycles, the portions of which are dark-gray-colored in the drawings, and the light-grayed-out portions are illustrative purpose only and form no part of the claimed design.

The dark and light grayed surfaces shown on the surface of the design drawings do not represent a color nor a design pattern and only represent shading features on the surface of the ornamental design.
